COLLAPSIBLE TUBE CAP

Francis B. Strang, Homestead, Pa.

Application October 10, 1932, Serial No. 637,168

2 Claims. (Cl. 221—60)

This invention relates to caps or closures for collapsible containers designed for dispensing semi-fluids or pastes and has for the primary object the provision of a device of the above stated character which may be conveniently opened and closed without detaching the cap or closure from the container, thereby obviating loss or misplacement of the cap or closure and further providing a device which when closed will prevent evaporation of the contents of the container or the entrance of foreign matter into the latter and permits the cost of manufacture of this device to be maintained at a minimum.

With these and other objects in view this invention consists in certain novel features of construction, combination and arrangement of parts to be hereinafter fully described and claimed.

For a complete understanding of my invention, reference is to be had to the following description and accompanying drawing, in which

Figure 1 is a fragmentary side elevation illustrating a container with a cap or closure applied thereto constructed in accordance with my invention.

Figure 2 is a similar view taken at right angles to Figure 1.

Figure 3 is a sectional view taken on the line 3—3 of Figure 2.

Figure 4 is a sectional view taken on the line 4—4 of Figure 3.

Figure 5 is an end view illustrating the container and its discharge neck.

Figure 6 is a fragmentary side elevation illustrating a modified means of attaching the cap or closure to the container.

Figure 7 is a similar view illustrating another modified form of attaching means acting as a tension medium for normally urging the cap or closure into a position for closing the container.

Figure 8 is a fragmentary side elevation illustrating a modified means of connecting the cap or closure to the container.

Figure 9 is a similar view taken at right angles to that shown in Figure 8.

Figure 10 is a fragmentary sectional view illustrating the form of invention shown in Figures 8 and 9.

Figure 11 is a fragmentary side elevation illustrating another modified form of my invention.

Figure 12 is a plan view of the form of invention shown in Figure 11 with the cap or closure removed.

Referring in detail to the drawing, the numeral 1 indicates the body of a collapsible tube

or container having formed integrally therewith a hollow semi-circular shaped neck 2, providing an arcuate-shaped outer face 3 and flat side faces 4 on which are formed socketed bearings 5 to receive inwardly directed ends 6 of a substantially U-shaped attaching element 7, the bight portion 8 thereof extending transversely of the arcuately curved face 3 and spaced therefrom and fitting in a groove 9 formed in a closure or cap 10 adapted for movement over the arcuate face and prevented from lateral movement with respect thereto by flanges 11 frictionally engaging the side faces 4. The neck is provided with a discharge opening 12 extending through the arcuate face 3 and adapted to be opened and closed by the cap or closure 10. The cap or closure upon its inner face is recessed to receive a gasket 13 adapted to seal the outlet opening 12 when the cap or closure is positioned thereover. The outer face of the cap or closure is recessed, as shown at 14, to permit a person's finger to readily fit on the cap without the danger of slipping from the latter during the actuation of the cap for opening and closing the outlet opening 12. The cap when positioned over the opening, the gasket frictionally engages the arcuate-shaped wall, thereby effectively sealing the contents of the tube to prevent evaporation or the entrance of foreign matter. The cap when moved to open or close the outlet opening 12 has a wiping contact with the arcuate face 3, removing therefrom foreign matter and any of the contents of the tube which may adhere thereto, thereby maintaining the device in a sanitary condition. The ends of the element 7 are connected to the neck slightly below center of the neck 2 to cause the cap to more tightly fit the neck when in a closed position.

If desired the journals 5 need not project beyond the side faces 4 and are more in the form of sockets formed directly in the side walls.

The journals 5 are notched, as shown at 15, to receive the arm portions of the connecting member 7 for the purpose of tensioning said arm portions when the cap is moved to an open position so that when said cap is released the arms automatically return the cap to a closed position. The notches are provided with diverging walls on which the arms ride when the cap is moved to an open position thereby tensioning said arms to cause closing of the cap when released.

As shown in Figure 6, journals 16 in the form of pintles may be provided in lieu of the journals 5 and the ends of the connecting member 7 may be bent into eye formation, as shown at 17, to

receive the journals 16 for pivotally connecting the connecting member 7 to the neck.

As shown in Figure 7 the connecting member 7 may be constructed from flexible metal and have its ends anchored to the neck, as shown at 18, so that when the cap is moved to an open position, as shown in dotted lines, the connecting member will be flexed and due to its material a certain amount of tension will be developed 10 therein to cause the cap to automatically assume a closed position when manually freed.

As shown in Figures 8 to 10, the neck 20 is of a similar shape to the neck shown in the other forms of my invention except the sides are provided with guide flanges 21 fitting within guide grooves 22 of a closure cap 23. The cap 23 thus connected to the neck may be slid relative thereto for the purpose of opening and closing the outlet opening thereof. It is preferable that the 20 guide flanges 21 increase in width opposite the discharge opening so as to bind the cap when disposed over the opening and prevent the latter from accidentally moving into an open position.

Projections 21' may be formed opposite the discharge opening and are received in the guide grooves of the cap to snap in notches 22' when the cap is in a closed position to prevent accidental movement of the cap from the stated position.

30 As shown in Figures 11 and 12 the neck 24 may be of segmental shape and flanged similar to the neck 20 and carrying thereon the cap 23. The flanges of the neck 24 project slightly beyond one end of the neck to form tips 25 which may be 35 bent angularly to prevent the cap from moving off of the neck after being once applied to said neck.

While I have shown and described the pre-

ferred embodiment of my invention, it will be understood that minor changes in construction, combination and arrangement of parts may be made without departing from the spirit and scope of my invention, as claimed.

Having described the invention, I claim:

1. A collapsible tube cap including a neck having an arcuate shaped outer face and flat side walls and a discharge opening in said outer face, a closure element slidably mounted on the outer face and opening and closing the discharge opening, a resilient substantially U-shaped attaching element having a bight portion connected to the closure element and arm portions overlying the side walls, and means for connecting the ends of the arm portions to the side walls to tension the arm portions by the closure element moving into a position to uncover the discharge opening whereby said arm portions act to move the closure element to cover the discharge opening when released from said position. 95

2. A collapsible tube cap including a neck having an arcuate shaped outer face and flat side walls and a discharge opening in said outer face, a closure element slidably mounted on the outer face and opening and closing the discharge opening, a resilient substantially U-shaped attaching element having a bight portion connected to the closure element and arm portions overlying the side walls, and socketed lugs on the side walls and receiving the ends of the arm portions whereby said arm portions become tensioned by the closure element moving in a position to uncover the discharge opening, said arm portions acting to move the closure element to cover said discharge 110 opening when released from said position. 105
